[57] CLAIM

The ornamental design for an acrylic night light cover in the form of a swan, as shown and described in FIGS. 1-14.

DESCRIPTION

FIG. 1 is a rear perspective view of a translucent frosted acrylic night light cover in the form of a swan, showing a night light fixture in phantom, according to my design;

FIG. 2 is a top view of my design;

FIG. 3 is a front view of my design;

FIG. 4 is a left side view of my design;

FIG. 5 is a right side view of my design;

FIG. 6 is a back view of my design;

FIG. 7 is a bottom view of my design;

FIG. 8 is a rear perspective view of a clear acrylic night light cover in the form of a swan, showing a night light fixture in phantom, according to my design;

FIG. 9 is a top view of my design;

FIG. 10 is a front view of my design;

FIG. 11 is a left side view of my design;

FIG. 12 is a right side view of my design;

FIG. 13 is a back view of my design; and,

FIG. 14 is a bottom view of my design.

The nightlight in phantom lines is shown for illustrative purposes only and forms no part of the claimed design.
